(57) **CLAIM**

The ornamental design for a retaining device for sheets and coverings, as shown and described.

DESCRIPTION

FIG. 1 is a top perspective view of a retaining device for sheets and coverings of the invention.

FIG. 2 is a top view of the retaining device for sheets and coverings of FIG. 1.

FIG. 3 is a bottom view of the retaining device for sheets and coverings of FIG. 1.

FIG. 4 is a front view of the retaining device for sheets and coverings of FIG. 1.

FIG. 5 is a rear view of the retaining device for sheets and coverings of FIG. 1.

FIG. 6 is a left end view of the retaining device for sheets and coverings of FIG. 1, with the right end view being a mirror image; and,

FIG. 7 is a left end view of the retaining device for sheets and coverings of FIG. 1, shown holding a sheet that is shown dashed that does not form part of the claimed invention.

1 Claim, 7 Drawing Sheets
